Attorneys.

UNITED STATES PATENT OFFICE.

JOHN WILSON, OF GLASGOW, SCOTLAND.

SUGAR-CANE MILL.

1,213,722.

Specification of Letters Patent. Patented Jan. 23, 1917.

Application filed October 1, 1915. Serial No. 53,570.

To all whom it may concern:

Be it known that I, JOHN WILSON, a subject of the British King, residing at 347 Cumbernauld road, Dennistown, Glasgow, Scotland, have invented certain new and useful Improvements in and Relating to Sugar-Cane Mills; and I do hereby declare the following to be a full, clear, and exact description of the invention, such as will enable others skilled in the art to which it appertains to make and use the same.

This invention relates to improvements in mills for crushing sugar cane or like substances, and embodies the method of arranging that class of mills, in which the rollers are in pairs, in such a way that a line drawn through the axes of each pair of rollers is parallel to similar lines drawn through the axes of the other pairs of rollers.

According to my invention I dispense with the usual form of headstock, and attach the bearings for the gudgeons of the rollers to the upper and lower sides respectively of pairs of rolled steel channel beams, having the inner sides of the channels in juxtaposition and facing each other, thus forming in effect a hollow box girder. The attachment of the bearings to the frame is such that the ends of the rollers rotate in the same plane as the outer faces of the channel beams, and the latter being inclined at a suitable angle, 45° or thereabout, the crushed cane drops from one pair of rollers to the following pair, guided by a plate stretched across the bottom of the channel beams, and by the inside faces of the channel beams.

My invention will be understood by reference to the accompanying drawings, in which:

Figure 1 is a section taken through the center lines of one pair of rollers; Fig. 2 is a sectional elevation taken through the bearings of the shaft appertaining to one pair of rollers; Figs. 3, 4 and 5 are elevations and cross section of the individual rollers; Fig. 6 is an elevation of the mill showing one method of actuating the several rollers; and, Fig. 7 is an elevation with the rollers in section.

Referring to the drawings, the necks of the shafts A, B, to which the rollers C, D, are respectively attached are carried in the bearings E, F. These bearings E, F, afore-

said are secured to the flanges of the rolled steel channel beams G at such positions that the plane formed through the center line of the rollers is inclined to the plane formed by the flanges of the channel beams G at 60 an angle of 75° or thereabout. The caps of these bearings are limited in their movement by the bolts H, which pass through the body of the bearings and behind each pair of the channel beams G, which are placed as shown 65 with their cavities facing inward, to form in effect a hollow box girder. The bolts H are secured to the bodies of the bearings with nuts J. The lower end of the bolts extend sufficiently to receive the bottom cap 70 K, which is secured by nuts J' in an immovable position. The upper end of the bolts J is extended to receive the cap L which is free to slide upward and terminates at a point sufficiently distant to receive an 75 other cap M, with steel springs N intervening between it and the said sliding cap L. These springs are of a strength proportionate to the size of the rollers, and may be kept in any degree of compression desired by 80 means of the nuts O on the extreme end of the bolts H.

The pairs of channel beams G on opposite sides of the mill are connected by a thin steel plate P attached to the bottom flanges. 85 This plate has openings to clear the bottom rollers, with an additional clearance sufficient to enable the expressed juice to fall through.

A light chute Q, Figs. 1 and 7, is suspended from the column R, Fig. 2, and held in position by suitable means. In the expression of the juice from the cane the juice drops from the surface of the rollers into the chute Q, and the crushed cane or begasse 95 slides down the surface of the plate P, seen in dotted lines in Fig. 1, to the next pair of rollers, and finally to the begasse carrier or elevator, not shown. To facilitate this sliding or falling movement, the channels G 100 are placed in an inclined position, preferably 45° to the horizontal plane. In Fig. 3, I show one system of forming the grooves on surfaces of the respective rollers, these grooves being of the zigzag type. In the 105 apparatus herein described various types of grooves in the rollers are shown.

When more than three pairs of rollers are employed, I may form the grooves of the second pair of rollers C', D' similar to those 110

of the first pair of rollers C, D, but of lesser pitch, the subsequent rollers being grooved as shown in the second set C', D', and third set C², D² of Fig. 5. I do not, however, 5 confine myself to any definite size or nature of groove or corrugation.

As it is necessary with this type of mill to increase the pressure progressively on each succeeding pair of rollers suitable means 10 must be provided for that purpose, and in Figs. 1, 2, and 7, one such method is illustrated. Springs N, of sufficient power are provided, as shown, above cap L of each top roller bearing. For practical purposes the 15 springs N may be all of equal power throughout, the increased pressure on the successive rollers being secured by screwing down the outer cap M more or less, according to the pressure found requisite.

20 On reference to Fig. 1, it will be seen that motion is imparted to the rollers by means of a wheel S, keyed to an extension at one end of the shaft of the lower roller. The upper roller obtains its motion from the 25 lower by means of pinions T, T', attached to extensions of their respective shafts at the opposite ends. The wheel S may either be a bevel wheel driven by a bevel pinion, or any other suitable gearing may be employed. 30 The bevel pinions are attached to a longitudinal shaft U, supported on bearings V, bolted to the outside of the channels G, as illustrated in Fig. 6. At the end of the shaft U, motion is obtained from a horizontal transverse shaft W, by means of 35 bevel gearing. This horizontal transverse shaft may in turn be driven from another horizontal superposed shaft Z, running at a higher speed through suitable spur gearing, 40 the bearings for both shafts being secured to the flanges of the channel beams G.

I claim:

1. In a cane mill having the rollers mounted in pairs, the combination with a housing comprising two pairs of oppositely disposed channel beams, the flanges of each pair on each side of the mill being turned toward each other to form a hollow box girder, a plate connecting the bottoms of the two box girders on opposite sides of the mill, said 50 plate being cut away to provide channels for the lower rollers and for the juice, bearings for each pair of rollers mounted on opposite sides of said hollow box girders, and tie bolts passing through the hollow 55 portion of said box girders and tying said bearings together, substantially as described.

2. In a cane mill having the rollers mounted in pairs, the combination with a housing comprising two pairs of oppositely disposed 60 channel beams, the flanges of each pair on each side of the mill being turned toward each other to form a hollow box girder, a plate connecting the bottoms of the two box girders on opposite sides of the mill, said 65 plate being cut away to provide channels for the lower rollers and for the juice, bearings for each pair of rollers mounted on opposite sides of said hollow box girders, and tie bolts passing through the hollow portion of 70 said box girders and tying said bearings together, with springs mounted on said tie bolts, and means for adjusting the compression on said springs, substantially as described. 75

In testimony whereof, I affix my signature, in presence of two witnesses.

JOHN WILSON.

Witnesses:

I. H. PEARSON,
F. MIDDLETON.
